(57) **CLAIM**

The ornamental design for an applicator head for percussive massage device, as shown and described.

DESCRIPTION

FIG. 1 is a front perspective view of an applicator head for percussive massage device, showing our new design; FIG. 2 is a rear perspective view thereof; FIG. 3 is a top plan view thereof, the bottom plan view, the left side view and the right side view being identical thereto; FIG. 4 is front view thereof; and, FIG. 5 is a rear view thereof. In FIGS. 1-5, broken lines show portions of the applicator head for percussive massage device which form no part of the claimed design.
